UNITED STATES PATENT OFFICE.

JAMES S. LOCHHEAD AND JOSEPH R. MILLER, OF PITTSBURGH, PENNSYLVANIA.

STRUCTURAL MEMBER MANUFACTURE.

Application filed March 8, 1922. Serial No. 542,151.

To all whom it may concern:

Be it known that we, JAMES S. LOCHHEAD and JOSEPH R. MILLER, citizens of the United States, residing in Pittsburgh, county of Allegheny, and State of Pennsylvania, have invented an Improvement in Structural Member Manufacture, of which the following description, in connection with the accompanying drawings, is a specification, like characters on the drawings representing like parts.

Our invention aims to provide an improved structural element having strength, light weight and convenient form, and which can be made at low cost.

In the accompanying drawings, wherein we have shown one embodiment of our invention for purposes of illustration, Fig. 1 is a side view of an I-beam of usual form, the web of which has been slotted or punched preparatory to further treatment according to our invention;

Fig. 2 is a similar view after rolling the flanges;

Fig. 3 is a cross-section of the same on the line 3-3 of Fig. 2, the original outline of the beam being shown in dotted lines;

Fig. 4 is a side view of the beam after rolling the web and flanges to reduce and elongate them;

Fig. 5 is a side view of the same after further rolling the flanges;

Fig. 6 is a cross-section of the beam after rolling the web and flanges, the cross-section being taken on the line 6-6 in Fig. 4 and showing the thickness before rolling in dotted lines;

Fig. 7 is a side view of the beam after separating the flanges to straighten out the web members or ties connecting the flanges;

Fig. 8 is a similar side view of the beam after again rolling the flanges to elongate the beam further;

Fig. 9 is a cross-section on the line 9-9 in Fig. 8 after separating and rerolling the flanges, the dotted lines showing the shape before rerolling the flanges; and

Figs. 10 and 11 are a side elevation and cross-section, respectively, of the finished element.

In the particular embodiment of our invention selected for illustration herein and shown in the drawings, referring particularly to Figs. 1 and 2, starting with an I-beam 11 of suitable cross-sectional shape, the web 12 is formed by slitting, punching or other

suitable means, into a series of more or less V-shape connecting members 13, having their diverging ends attached to the flanges 14. These V-shape web members 13 are so disposed that their converging ends point in the same direction, preferably away from the leading end of the beam as it passes through the slit-forming machine.

The connecting web members may have any suitable shape, and the open spaces between them may be varied as and where desired as may be found most advantageous in producing the form of finished product desired.

Following the slit-forming operation the beam is passed through suitable rolls, and the flanges 14 are rolled so as to elongate them without affecting the web portions, thereby separating the connecting members adjacent the flanges, leaving spaces or openings 15 between them narrowing down at the bases of the connecting members and adjacent the flanges, as shown in Fig. 2. Next the entire beam is preferably reduced and elongated by rolling the web and flanges, thereby elongating not only the flanges but the connecting members as well, as illustrated in Fig. 4. This may be followed by again rolling the flanges alone to elongate them as shown in Fig. 5, and to further separate the connecting members 13. The effect of the rolling upon the connecting members is to obtain the desired additional length thereof, accompanied by additional compactness and strength. The number of rolling operations on the web and flanges may be varied to secure any reduction and elongation desired.

Following the rolling, the beam is passed through suitable guides, or operated on by a press, or by other means adapted to separate the flanges 14, thereby changing the lines or straightening the connecting web members to form ties 16 as illustrated in Fig. 7. If desirable the beam as a whole, or its flanges 14 or web separately, may be subjected to such further rolling or action as may be necessary or desired to further shape, straighten or align the component parts or any of them, and to produce the desired ultimate form, such, for example, as illustrated in Figs. 8 to 11, and producing a light and strong beam suitable for any structural purpose. All of the operations are preferably performed hot.

Our invention is applicable to all types

of web members for structural and other purposes, and obviously is not restricted to the particular embodiment thereof herein illustrated and described.

5. Having disclosed one illustrative embodiment of our invention, what we claim and desire to secure by Letters Patent is as follows:

10. 1. A process of forming structural members by dividing the intermediate portions of a rolled shape into a series of inclined strips connecting the marginal portions, rolling said shape to elongate said strips, and separating the marginal portions to bend said strips transversely across the intervening space to form rigid ties.

20. 2. A process of forming structural members by dividing the intermediate portions of a rolled shape into a series of lengthwise extending transverse web members connecting the marginal portions, rolling said shape to elongate said web members and separating the marginal portions to bend said ties transversely across the intervening space to form an open work web.

30. 3. A process of forming structural members by dividing the intermediate portions of a rolled shape into a series of V-shaped members connecting the marginal portions, rolling said shape to elongate said members and separating the marginal portions to bend said members transversely across the intervening space to form an open work web.

40. 4. A process of forming structural members by dividing the intermediate portions of a rolled shape into a series of strips connecting the marginal portion, rolling said shape to elongate said strips and marginal portions, and separating the marginal portions to bend said strips transversely across the intervening space to form an open work web.

45. 5. A process of forming structural members by dividing the intermediate portion of a rolled shape into a series of transverse strips connecting the marginal portions, the middles of said strips being displaced lengthwise of the member from the ends of

the strips, rolling said shape to elongate 50 said strips, and separating the marginal portions to bend said strips transversely across the intervening space to form an open work web.

6. A process of forming structural members by dividing the intermediate portions of a rolled shape into a series of angularly disposed members connecting the marginal portions, rolling said shape to elongate said connecting members and marginal portions, 60 and separating the marginal portions to bend said connecting members transversely across the intervening space to form an open work web.

7. A process of forming structural members by dividing the intermediate portion of a rolled shape into a series of inclined ties connecting the marginal portions, rolling said shape to elongate said marginal portions and separate said ties, and separating the marginal portions to bend said ties transversely across the intervening space to form an open work web.

8. A process of forming structural members by dividing the intermediate portions of a rolled shape into a series of inclined ties connecting the marginal portions, rolling said shape to elongate said marginal portions and separate said ties, rolling said ties to elongate them, and separating the 80 marginal portion to bend said ties transversely across the intervening space to form an open work web.

9. A process of forming a structural member by forming the intermediate portion of 85 a rolled shape, to produce a series of inclined strip portions connecting the marginal portions, rolling said shape to elongate said strip portions in a direction transverse to the member as a whole, and separating the marginal portions to bend said strip portions transversely across the intervening space to form rigid ties.

In testimony whereof, we have signed our names to this specification.

JAMES S. LOCHHEAD.
JOSEPH R. MILLER.
